W. J. COLEMAN.
GUARD DEVICE FOR VESSELS.
APPLICATION FILED JUNE 6, 1917.

1,235,440.

Patented July 31, 1917.

UNITED STATES PATENT OFFICE.

WILLIAM J. COLEMAN, OF HYDE PARK, MASSACHUSETTS.

GUARD DEVICE FOR VESSELS.

1,235,440.

Specification of Letters Patent. Patented July 31, 1917.

Application filed June 6, 1917. Serial No. 173,209.

To all whom it may concern:

Be it known that I, WILLIAM J. COLEMAN, a citizen of the United States, residing at Hyde Park, in the county of Suffolk and State of Massachusetts, have invented 5 certain new and useful Improvements in Guard Devices for Vessels, of which the following is a specification, reference being had to the accompanying drawings.

10 This invention relates to an improved guard device to protect vessels from torpedo attack by submarines, and has for its primary object to provide a device for this purpose which will present a barrier in the 15 path of the torpedo and prevent the same from penetrating the hull of the vessel.

It is another and more particular object 20 of my invention to provide a guard device for vessels embodying a plurality of units provided with means to receive intersecting iron rods, said rods having angular portions, and longitudinally extending rails to which the units are secured and held in 25 assembled relation, the angular portions of said rods being tapered to a point and projecting outwardly from the side of the vessel's hull and below the water line.

It is also another object of my invention 30 to provide protecting or guard means for vessels as above characterized, which is relatively simple in its construction, strong and durable, and therefore capable of manufacture at small cost and which will also be very effective for the purpose in view.

35 With the above and other objects in view, my invention consists in the novel features of construction, combination, and arrangement of parts to be hereinafter more fully described, claimed and illustrated in the 40 accompanying drawing, in which,

Figure 1 is a perspective view showing my improved armor disposed upon one side of a vessel's hull;

Fig. 2 is a sectional view taken on the 45 line 2—2 of Fig. 1;

Fig. 3 is a perspective view showing one of the guard units and one of the protecting members separated;

Fig. 4 is a similar view of one of the 50 guard units which is arranged in the longitudinally extending channel-shaped rail; and

Fig. 5 is an enlarged fragmentary elevation of the guard.

55 Referring in detail to the drawing, 5 designates an upper rail and 6 an intermedi-

ate rail. The latter rail is of channel-shaped form as clearly shown in Fig. 2, the channel therein facing toward the hull of the vessel. This rail is centrally provided with a longitudinally extending series of spaced openings 7. Metal blocks 8 are arranged in the channel of the rail 6 and suitably secured thereto, each of said blocks having one end of a rod 9 centrally fixed therein. The rods 65 in these blocks are adapted to project outwardly through the openings 7, said rods gradually tapering to a point at their other ends.

Additional metal blocks or units 10 are 70 also provided and are formed upon their opposite ends with the lips 11. These lips are adapted to be suitably secured to the longitudinal flanges 12 of the rail 6, a series of the blocks 10 being arranged above and 75 below this rail. The lips 11 on one end of the upper series of units 10 are secured to the rail 5. These latter blocks or units are provided in one face with intersecting grooves or channels 13, and the central unit 80 in the series receives the cruciform member 14 consisting of intersecting rods having angular end portions 15 which are adapted to project at right angles to the block 10 and outwardly between the meeting edges 85 of the adjacent blocks, said ends 15 of the rods being also pointed or sharpened. The remaining units 10 in the series are each provided with only three of the outwardly 90 extending rods 15 so that there will be provided in the completed structure, longitudinal series of spaced, outwardly projecting rods which are alternately arranged with respect to each other in different vertical planes. Between the outwardly extending 95 guard rods, vertical openings 16 are formed through the blocks or units 8 and 10, and through the same the wire strands 17 extend, the upper ends of said strands being fixed to the rail 5. Thus, there is provided 100 a very effective guard for the hull of the vessel so that there will be a minimum of exposed surface with which the torpedo could possibly contact.

From the foregoing description, taken in 105 connection with the accompanying drawing, the construction, manner of use, and several advantages of the device will be clearly and fully understood. The multiplicity of outwardly projecting rods or prongs serve 110 to deflect the torpedo or cause its explosion before it can strike the hull of the vessel,

thus preventing injury to the latter. Any desired number of the series of blocks or units can be utilized and the guard device either attached by means of the top rail 5 directly to the hull of the vessel about on the water line; or the guard may be suspended by any suitable means in spaced relation to the side of the vessel's hull. The vertical wire strands 17 afford an additional means 10 of protection, and reduce to a minimum the possibility of the projectile piercing the armor and coming in contact with the vessel. The blocks or units employed in the guard construction may be of any desired thickness 15 and various other shapes or forms of these units may also be employed if desired. It is, therefore, to be understood that while I have herein shown and described the preferred construction and arrangement of the 20 several elements employed, the same are susceptible of considerable modification, and I, therefore, reserve the privilege of adopting all such legitimate changes as may be fairly embodied within the spirit and scope of the 25 invention as claimed.

Having thus fully described my invention, what I desire to claim and secure by Letters Patent is:

1. A guard of the character described 30 comprising a plurality of series of units arranged in superposed relation, guard elements projecting outwardly from the units and alternately arranged in staggered relation, and connecting means between the corresponding units.

2. A guard of the character described comprising a plurality of series of units arranged in superposed relation, guard elements projecting outwardly from the units 40 and alternately arranged in staggered relation, and flexible means connecting the corresponding units of the guard to each other.

3. A guard of the character described comprising a channel-shaped rail centrally 45 provided with a longitudinal series of spaced openings, units arranged in the chan-

nel of the rail, each unit having a guard element fixed therein and projecting outwardly through one of the openings in the rail, an additional longitudinally extending series of 50 units secured to each edge of the rail, and a plurality of guard elements secured to each of the latter units and projecting outwardly therefrom.

4. A guard of the character described 55 comprising a channel-shaped rail centrally provided with a longitudinal series of spaced openings, units arranged in the channel of the rail, each unit having a guard element fixed therein and projecting outwardly 60 through one of the openings in the rail, an additional longitudinally extending series of units secured to each edge of the rail, a plurality of guard elements secured to each of the latter units and projecting outwardly 65 therefrom, and flexible wires tying the corresponding units of the several series together.

5. A guard of the character described comprising a channel-shaped rail centrally 70 provided with a longitudinal series of spaced openings, units arranged in the channel of the rail, each unit having a guard element fixed therein and projecting outwardly through one of the openings in the rail, an additional longitudinally extending series of 75 units secured to each edge of the rail, a plurality of guard elements secured to each of the latter units and projecting outwardly therefrom, each of said units having spaced 80 openings formed therethrough, the openings in the units of one series coinciding with the openings in the corresponding units of the other series, and flexible wires extending through said openings and tying the series 85 of units together.

In testimony whereof I hereunto affix my signature in the presence of two witnesses.

WILLIAM J. COLEMAN.
